RETRIEVING TOOL

Herbert C. Otis, Dallas, Tex., assignor to Otis Engineering Corporation, Dallas, Tex., a corporation of Texas

Application December 15, 1945, Serial No. 635,235

5 Claims. (Cl. 166—1)

1

This invention relates to new and useful improvements in retrieving tools.

In wells wherein removable subsurface flow controls have been installed in the flow conductor, and more particularly in wells wherein more than one producing zone is present and in which flow controls of the type illustrated in the patent to Herbert C. Otis, No. 2,246,811, issued June 24, 1941, are installed, it is frequently difficult to safely remove the flow control because of unbalanced pressure conditions. Such conditions of unbalanced pressure may result in the flow control being blown up the well flow conductor as it is initially moved from its position within the conductor, thus causing the flexible steel line used in removing the control to become tangled or "balled up." In such event, the tangled line must first be "fished" out of the well before the flow control can be fully removed from the conductor.

Further, other types of subsurface well tools frequently are difficult to remove by means of a small flexible steel line and it is necessary to utilize some other means for applying the force necessary to retrieve such tools.

It is, therefore, one object of the invention to provide an improved retrieving tool which is designed to utilize the natural well pressure or an injected fluid pressure for extracting well devices from a well conductor.

A particular object of the invention is to provide an improved retrieving tool having sealing means which is arranged to be expanded to sealing position prior to applying fluid pressure thereagainst to remove the well tool.

A further object of the invention is to provide a retrieving tool of the character described which is provided with a by-pass passage to permit the device to be lowered through fluid and which is normally closed when fluid pressure is applied to actuate the retrieving tool.

Still another object of the invention is to provide in a retrieving tool of the character described means for preventing premature setting or expansion of the packing means.

An important object of the invention is to provide a retrieving tool, adapted to be operated by fluid pressure to remove well devices from a well flow conductor, which has a plurality of sealing elements incorporated therein, whereby the retrieving tool will successfully maintain its seal as couplings are passed, so that if one of the sealing elements is positioned opposite the recess between the ends of joints of pipe at a coupling the other sealing element will engage the wall of

2

the pipe to permit proper functioning of the device.

A still further object of the invention is to provide a retrieving tool of the character described which is adapted to be run into a well conductor upon a flexible steel line or dropped into the well conductor to engage a well device to be removed from such conductor.

A still further object of the invention is to provide a retrieving tool of the character described which is so arranged that fluid may be pumped downwardly through the conductor but which prevents upward flow of fluid therewith.

Additional objects and advantages of the invention will be apparent from the reading of the following description of devices constructed in accordance with the invention, and reference to the accompanying drawings thereof, wherein:

Figure 1 is a view, in elevation, of a retrieving tool constructed in accordance with the invention and showing the same engaging a well device in a well flow conductor.

Figure 2 is an enlarged view, partly in elevation and partly in section, illustrating the packing assembly of the retrieving tool, and showing the packing unexpanded,

Figure 3 is a view similar to Figure 2, illustrating the packing in its expanded position,

Figure 4 is a view, partly in elevation and partly in section, of a modified form of the packing element of the retrieving tool and showing the packing unexpanded,

Figure 5 is a view similar to Figure 4, showing the packing in expanded sealing position,

Figures 6, 7, 8 and 9 are horizontal cross-sectional views taken on the lines 6—6, 7—7, 8—8 and 9—9 of Figure 4.

In the drawings the numeral 10 designates an elongate tubular mandrel having an external annular shoulder 11 formed at its mid-portion. A sealing element 12, such as an inverted pump cup, is supported on said shoulder, and a wear ring 13, having an auxiliary packing ring 14 for sealing between said wear ring and mandrel, is mounted on the mandrel above the pump cup and is held in place thereon by means of a packing nut 15 which is threaded onto the upper end of said mandrel.

An elongate retrieving member 16 is also screw threaded onto the upper end of the mandrel and has its upper portion reduced above a shoulder 16a. This reduced portion has a retrieving connection 17 formed at its upper end. The bore of the retrieving member is also reduced to form a valve seat 18 which is arranged to have a valve

19 seat thereon to close the bore of the retrieving member against upward fluid flow.

The valve has a reduced elongate stem 19a which extends substantially above the upper end of the retrieving member, as clearly shown in Figure 2, and an enlarged head or cap member 20 is threaded onto the upper end of the valve stem. The lower portion of the valve is provided with external guide fins 21 for guiding its longitudinal motion in the bore of the mandrel. A helical coiled spring 22 engaging the lower ends of the fins 21 is supported at its lower end upon an internal shoulder 23 formed in a housing 24 which is screw threaded into the lower end of the mandrel 10. Therefore, the spring exerts its force to maintain the valve 19 seated against the seat 18 in the retrieving member.

An external annular flange 25 is formed at the lower end of the housing and an elongate packing expanding sleeve 26, having an internal annular flange 27 which is slidably confined between the lower end of the mandrel and the annular flange 25 on the spring housing, is slidable with relation to the mandrel 10. The packing expanding sleeve is provided with an upwardly converging or wedge surface 28 at its upper end which is adapted to engage the lower end of the pump cup or packing 12 to force the same radially outward into sealing engagement with the wall of a well tubing T in which the device is adapted to be used.

A cylindrical box or connecting member 29 is screw threaded into the lower end of the packing expanding sleeve and is provided with internal screw threads 30 at its lower end for receiving the screw threaded pin 31 at the upper end of a retrieving tool P. Laterally extending fluid courses 32 provide for flow of fluid from the exterior of the box into the bore of the same and upwardly through the spring housing and mandrel to the valve and seat at the upper end of the packing element S.

The retrieving tool P may be of any suitable type, but the tool illustrated is similar to that shown in the patent to Herbert C. Otis, No. 1,898,261, issued February 21, 1933.

The tool P includes a sub 34 which is provided with the upstanding screw threaded pin 31 at its upper end, and has an elongate cylindrical housing 35 surrounding a core 36 on which supporting elements or dogs 37 are swingably mounted. The dogs are adapted to engage over a retrieving connection 49 on the upper end of the well device D which is desired to be removed from the well.

In use, the packing assembly S is connected to the retrieving tool P, as shown in Figure 1, and either dropped directly into the well tubing or lowered slowly therein with a suitable running tool until the supporting elements or dogs 37 at the lower end of the retrieving tool P engage the retrieving connection 40 of the device which is desired to be removed from the well tubing.

It is preferable that the assembly be lowered into the well tubing by means of a lowering mechanism operable by means of a flexible wire line (not shown). A running tool 45 having a downwardly facing cylindrical bowl 46 formed thereon is connected to the lowering mechanism and has its lower end riveted, or otherwise releasably secured, to the upper end of the retrieving member of the packing assembly, as clearly shown in Figure 2. In this position the cap 20 at the upper end of the valve stem engages the closed upper end of the bowl of the running tool and is depressed to maintain the valve in open

position whereby well fluid may flow past the packing assembly S. Rivets or shear pins 47 extending through radial openings formed in the skirt of the bowl and in the retrieving connection 5 support the assembly as it is lowered into the well tubing.

When the retrieving tool P has engaged the well device D which is desired to be removed from the well, application of downward force to the 10 running tool will shear the pins 47 and permit the bowl to further telescope the upper end of the retrieving member so that the lower end of the running tool will engage the shoulder 16a on the retrieving member. When the running tool 15 engages the shoulder, further application of a downward force to the running tool transmits a downward force to the mandrel 10 and the packing means or pump cup 12 carried thereby to move the same downwardly with respect to the 20 packing expanding sleeve 26. As the mandrel moves downwardly, the packing expanding surface 28 engages the lower end of the pump cup 12 and moves the same radially outward into contact with the wall of the well tubing, as clearly 25 shown in Figure 3. Since the shear pin has been fractured, the running tool may be removed from the well by means of the flexible line lowering mechanism, and the retrieving tool is left in the position shown in Figure 3, wherein the valve 30 closes the bore of the mandrel and the pump cup is expanded to initial sealing position.

Now, if the well surface connections (not shown) are opened to permit a flow of well fluid upwardly through the well tubing, such well fluid 35 will be sealed off by the pump cup packing element and cannot pass through the bore of the mandrel because valve 19 is closed. Therefore, the well fluid will exert its pressure upwardly 40 against the cup and mandrel to lift the same and, the packing cup having been mechanically initially forced to sealing position, the mandrel and the spring housing connected thereto will be moved upwardly with respect to the expanding sleeve 26 until the internal flange 27 on the 45 expanding sleeve engages the external flange 25 on the lower end of the spring housing and thereby lifts the expanding sleeve 26 and the retrieving tool P to which it is connected by means of the box member 29. Continued application of the 50 well fluid pressure will move the mandrel and the retrieving tool carried thereby upwardly to lift the well device from its position within the well tubing.

Since the flexible line lowering mechanism has 55 been previously removed from the well tubing, it is obvious that any upward movement of the retrieving tool and the packing assembly, as the well device D is released from its position, will not cause the "balling up" or tangling of the flexible line which might occur had the line been connected to the retrieving tool in the customary manner.

Also, considerable force may be applied to the 60 retrieving tool in this manner, since the well pressure is acting against the entire area of the sealing or packing assembly S. It will readily be seen that a well pressure of 2000 pounds per square inch acting against a 3 square inch area will exert an upward force of approximately 6000 65 pounds. This force may be in excess of the force which could be applied by means of a small flexible steel line such as is commonly used in retrieving removable subsurface well devices.

When lowering the packing assembly S by 70 means of the running tool 45, it may be desirable

to prevent movement of the packing expanding sleeve 26 with relation to the pump cup 12 to prevent premature expansion of said cup into sealing position. Such movement of the packing expanding sleeve may be prevented by providing a frangible pin 49 in a transverse opening formed in both the sleeve and spring housing 24. Obviously, when the running tool is jarred downwardly to apply a downward force to the mandrel 10 and the spring housing carried thereby, the frangible pin 49 will be sheared to permit relative motion between said sleeve and mandrel. The strength of the frangible pin, however, will normally be such that premature relative motion between such members will be prevented.

From the foregoing, it will be seen that an improved retrieving mechanism has been provided for removing well devices from well tubing, which includes a retrieving tool P and packing assembly S designed to utilize the pressure of the well fluid to release the well device.

It will further be seen that the packing assembly is provided with sealing means which may be initially mechanically expanded to sealing position prior to the application of fluid pressure thereagainst. Such initial mechanical expansion permits application of fluid pressure against the sealing member without unduly flowing the well to set the sealing member. It will also be seen that the packing assembly is provided with means for by-passing fluid past the sealing means as the device is lowered into the well to prevent premature expansion of the sealing means to sealing position. Fluid may also be pumped downwardly past the packing assembly, if desired, since the valve 19 opens downwardly. Further, means is provided for preventing actuation of the packing expanding member prematurely. Also, the device may be run into the well on a flexible line lowering mechanism and the sealing element expanded to sealing position mechanically to permit utilizing fluid pressure to remove the well device; and, the wire line lowering mechanism may be removed from the well to prevent "balling up" or tangling the flexible line as the well device is released.

Once the well device has been loosened from its position within the tubing, a suitable retrieving tool, similar to the retrieving tool P, may be lowered into the well tubing upon the flexible line lowering mechanism (not shown) to engage the retrieving connection 17 at the upper end of the retrieving member, and the entire assembly may be lifted out of the well tubing by means of the wire line mechanism.

A modified form of packing assembly is illustrated in Figures 4 and 5. This type of packing assembly is particularly adapted to assure that a sealing member is expanded into engagement with the wall of the well pipe even though one of the sealing elements be positioned opposite the recess at a coupling between two joints of pipe. It is also adapted for use in deep high pressure wells within the retrieving assembly must be flowed up the well conductor for a considerable distance, since more than one packing element is provided to assure operation of the assembly even though one packing element be worn out or torn off or otherwise destroyed.

An elongate tubular mandrel 50 has an external annular shoulder 51 formed thereon and is adapted to have a sealing element 52, such as an inverted pump cup, positioned thereon and confined between said shoulder and a wear ring 75

53. The wear ring has an auxiliary packing ring 54 for sealing between said wear ring and the mandrel, and is held in place on the mandrel by means of a packing nut 55 which is threaded on to the mandrel in the same manner as in the form previously described.

This mandrel has an elongated reduced upwardly standing neck 56 upon which a second packing element is mounted. A tubular packing support 57 is slidable upon the reduced neck 56 and has an external annular flange 58 at its lower end. A packing element 59, such as an inverted pump cup, is confined between said flange and a wear ring 60 having an auxiliary packing ring 61, similar to the ring 53 and packing 54. The wear ring is held on said support by a packing nut 62 threaded onto the upper end thereof.

The packing support 57 is slidable toward and from the expander member 63 which is threaded onto the mandrel 50 and has an upwardly converging packing expanding surface or wedge 64 at its upper end. The packing element or cup 59 on the support is adapted to engage said expander member, and downward motion of the support toward the expander will cause the lower end of the packing element or pump cup to be moved radially outward into initial sealing engagement with the wall of the well pipe.

An elongated packing gland member 65 having a plurality of rings of chevron type packing 66 confined therein for sealing between said gland and the mandrel neck 56 is screw threaded onto the upper end of the packing support member 57 and is confined on the mandrel neck 56 by a retaining nut 67 which is threaded onto the upper end of said mandrel neck and engages the upper end of the packing gland member.

An elongate retrieving member 68 telescopes the upper end of the mandrel neck and is screw threaded onto the upper end of the packing gland member. The upper end of the retrieving member is reduced to provide a shoulder 69 and a retrieving connection 70 is formed at the extreme upper end of the reduced portion of the retrieving member.

The bore of the mandrel 50 is enlarged below the neck portion 56 to provide a valve seat 71 which is adapted to have a valve member 72 seat thereon to close the bore of the mandrel 50 against upward fluid flow. The valve member is provided with external guide fins 73 for guiding its longitudinal motion in the bore of the mandrel, and a helical coiled spring 74, engaging the lower ends of the fins 73, has its lower end supported upon an internal shoulder 75 formed in a spring housing 76 which is screw threaded into the lower end of the mandrel 50. It will be seen that the spring exerts its force to normally maintain the valve seated against the seat in the bore of the mandrel.

An external annular flange 77 is formed at the lower end of the spring housing and an elongate packing expanding sleeve 78, having an internal annular flange 79 which is slidably confined between the lower end of the mandrel 50 and the annular flange 77 on the spring housing, is slidably longitudinally with relation to the mandrel 50. The packing expanding sleeve is provided at its upper end with an upwardly converging or wedge surface 80 which is adapted to engage the lower end of the pump cup or sealing element 52 to force the same radially outward into sealing engagement with the wall of the well tubing in which the device is used.

A cylindrical box or connecting member 81 is

screw threaded into the lower end of the packing expanding sleeve and is provided with internal screw threads 82 at its lower end for receiving the screw threaded pin 31 at the upper end of the retrieving tool P. Laterally extending fluid courses 83 provide for flow of fluid from the exterior of the box into the bore of the same and upwardly through the spring housing and mandrel to the valve and seat therein.

The valve 32 has an elongate stem 72a formed integrally therewith which extends upwardly through the bore of the mandrel neck 56 and substantially above the upper end of the retrieving member 68, as clearly shown in Figure 4. This stem is guided in its longitudinal motion in the mandrel neck by means of radial fins 84 which are arranged to slide in the bore of said neck. An enlarged head or cap member 85 is threaded onto the upper end of the valve stem for engagement by a running tool in the same manner as has been previously explained.

If desired, a frangible pin 86 may be provided in a transverse hole formed in the packing expanding sleeve 78 and the lower end of the spring housing 77 for preventing premature movement of the packing expanding sleeve relative to the mandrel and the packing or cup 52 carried thereby. A similar shear member or rivet 87 may be inserted into a radial opening extending through the retrieving member 68 and into an annular groove formed in the retaining nut 67, for preventing premature movement of the packing support 57 with relation to the expander member 63. In this manner premature mechanical expansion of the packing element or cup to sealing position may be prevented. The strength of the fragile pin and rivet will normally be such that premature relative motion of the packing expanding sleeve 78 and the packing support 57 will be prevented, but the pin and rivet may be readily sheared upon the application of a downward force to the shoulder 69, as has been previously explained. Further, the size of the pin and the rivet may be so chosen that one or the other will shear first to permit initial setting of either packing element or cup, as desired. Obviously, the shear pin 86 or the rivet 87, or both may be omitted if desired.

In use, the running tool 45 is releasably connected to the upper end of the retrieving member 68, as has already been explained, and the complete assembly lowered into the well tubing on a lowering mechanism operated by means of a flexible wire line (not shown). When the retrieving tool P has engaged the well device which is desired to be removed from the well, application of downward force to the running tool will release the connection of the lowering mechanism to the retrieving member, whereupon further application of downward force to the running tool of the lowering mechanism will transmit a downward force to the shoulder 69 on the retrieving member to move the same downwardly. As the retrieving member is moved downwardly, the packing support 57 is moved toward the expanding member 63 and the packing element 59 is engaged by the expanding surface 64 to move the lower end of the packing element or cup radially outward into contact with the wall of the well tubing, as clearly shown in Figure 5. Further application of downward force will cause the mandrel 50 to move downwardly relative to the packing expanding sleeve 78 and thereby bring the cup 52 into engagement with the expanding surface 80 to mechanically expand said

cup into sealing engagement with the well tubing in the same manner as in the previously described form of the invention.

Since the running tool of the wire line lowering mechanism has been disconnected from the retrieving member 68, the lowering mechanism and running tool may be removed from the well, leaving the retrieving tool assembly in the position illustrated in Figure 5, wherein the valve 32 closes the bore of the mandrel and the pump cups are expanded to initial sealing position.

Now, opening the well surface flow controls (not shown) to permit an upward flow of well fluid through the well tubing will cause the well fluid to exert its pressure upwardly against the cup and mandrel to lift the same and remove the well device from its position in the well tubing.

Obviously, should either of the packing elements or cups 52 or 59 be positioned opposite the recess at a coupling between two joints of tubing, the other packing element or cup will be expanded into sealing engagement with the wall of the tubing and the device will function properly.

Furthermore, should either of the packing elements or cups become worn or be torn off the packing assembly, the other cup will still seal between the tubing and the packing assembly to permit proper functioning of the retrieving assembly. Other functions and advantages of this form of the invention are the same as those enumerated for the form first described.

Obviously, the packing element S may be used with other well tools, if desired, to provide for an initial mechanical expansion of cup type sealing elements to sealing position in a well flow conductor.

The above description of the invention is explanatory only, and changes in details of the constructions illustrated may be made by those skilled in the art, within the scope of the appended claims, without departing from the spirit of the invention.

What I claim and desire to secure by Letters Patent is:

1. A retrieving tool for engaging and elevating removable well devices within a well flow conductor and including, a tubular mandrel, expansible packing means mounted externally on the mandrel and initially unexpanded, an expander sleeve slidable on the mandrel below the packing means for engaging and expanding the packing to initial sealing engagement with the bore wall of a well conductor, valve means in the mandrel normally closing the bore of the mandrel against upward fluid flow therethrough, an engaging and supporting device connected to the lower end of the expander sleeve and having depending supporting means for engaging and supporting a well device in the flow conductor, and means operable from the well surface for moving the mandrel and packing downwardly relative to the expander sleeve to expand the packing into sealing engagement with the bore wall of the flow conductor to close the bore of such conductor against upward fluid flow whereby well fluid pressure below the retrieving tool will force the same upwardly to lift the removable well device in the conductor.
2. A retrieving tool including, a mandrel, an initially unexpanded expansible downwardly facing sealing cup mounted on the exterior of the mandrel, an expander sleeve having a wedge surface at its upper end and slidably longitudinally on the mandrel below the sealing cup, releasable

means initially holding said sleeve against movement longitudinally of the mandrel and spaced from the sealing cup, an engaging and supporting device connected with the lower end of the sleeve and having depending yieldably mounted supporting elements disposed to engage and support a well device in a well flow conductor, the mandrel and sealing cup being movable downwardly with respect to the expander sleeve when the releasable means is released to move the cup into engagement with the wedge surface on the sleeve to expand the cup into sealing engagement with the bore wall of the flow conductor to close the bore of the conductor against upward flow whereby well fluid pressure below the retrieving tool will force the same upwardly to lift a removable well device in the conductor.

3. As a sub-combination in a retrieving tool, a packing assembly including, an elongate tubular mandrel, a downwardly facing initially unexpanded expansible sealing cup mounted exteriorly on the mandrel, an elongate expander sleeve slidable on the mandrel below the cup and having an expander wedge at its upper end engageable by the downwardly facing cup to expand the cup into initial sealing engagement with the bore wall of a well flow conductor, a frangible connection between the sleeve and mandrel initially holding said sleeve in a position on the mandrel spaced below the cup, a valve member in the bore of the mandrel normally closing the bore of the mandrel against upward fluid flow therethrough, and a connecting member connected with the lower end of the expander sleeve and providing for connection of an engaging and supporting device with said sleeve.

4. As a sub-combination in a retrieving tool, a packing assembly including, an elongate tubular mandrel, valve means normally closing the bore of the mandrel against upward fluid flow therethrough, a first downwardly facing initially unexpanded expansible sealing cup mounted exteriorly on the mandrel, an expander sleeve having an expander wedge at its upper end slidable longitudinally on the mandrel below the cup, first frangible means initially holding said expander sleeve in a position spaced from the sealing cup, an expander wedge fixed on the mandrel above the sealing cup, a packing sleeve slidable on the mandrel above the expander wedge, a second downwardly facing initially unexpanded expansible sealing cup carried by said packing sleeve and arranged to engage the expander wedge on the mandrel to be moved to initial sealing engagement with the bore wall of a well flow conductor when the packing sleeve is moved downwardly toward the expander wedge, second frangible means connecting the packing sleeve with the mandrel to prevent movement of the sleeve toward the expander wedge and having greater strength than said first frangible means connecting the expander sleeve and mandrel, said packing sleeve extending above the upper end of the mandrel and arranged to be engaged by a downwardly acting jarring device, whereby the

first frangible connection between the expander sleeve and mandrel is initially sheared to permit the mandrel to move downwardly with respect to the expander sleeve to expand the first packing cup into initial sealing engagement with the bore wall of the well flow conductor and to limit further downward movement of the mandrel, the second frangible means being frangible to permit the packing sleeve and cup to move downwardly toward the expander wedge on the mandrel to expand said second cup into initial sealing engagement with the bore wall of the flow conductor whereby the bore of the conductor is closed against upward fluid flow and well fluid pressure from below the packing assembly will force the same upwardly in the conductor.

5. A retrieving tool adapted to be lowered by means of a flexible line lowering mechanism into a well flow conductor for engaging and retrieving a well device removably mounted in said well flow conductor and including, a tubular mandrel, an initially unexpanded expansible downwardly facing packing cup mounted exteriorly on the mandrel, an expander sleeve having a wedge surface at its upper end slidable longitudinally on the mandrel below the cup and engageable by the packing cup upon downward movement of the mandrel and cup with respect to the expander sleeve, a releasable connection between the mandrel and expander sleeve initially holding the wedge surface of the sleeve spaced from the packing cup and releasable by downward force applied to the mandrel by the flexible line lowering mechanism to permit the mandrel and cup to move downwardly until the cup engages the expander wedge on the sleeve and is moved by said expander wedge into initial sealing engagement with the bore wall of a well flow conductor for sealing between the mandrel and said flow conductor, valve means normally closing the bore of the mandrel against upward fluid flow therethrough whereby the bore of the conductor is closed by the retrieving tool and fluid pressure in the conductor below the retrieving tool acts upwardly against the retrieving tool to lift the same, and an engaging and supporting device connected with the expander sleeve and having depending supporting members for engaging and supporting a removable well device.
